UNITED STATES PATENT OFFICE.

ALBERT KRAUTH, OF HAMILTON, OHIO.

SHARPENING-MACHINE.

1,261,136.

Specification of Letters Patent.

Patented Apr. 2, 1918.

Application filed September 10, 1915. Serial No. 49,956.

To all whom it may concern:

Be it known that I, ALBERT KRAUTH, a citizen of the United States, and residing at Hamilton, in the county of Butler and State 5 of Ohio, have invented a new and useful Improvement in Sharpening-Machines, of which the following specification is a full disclosure.

My invention relates to a knife sharpening mechanism for slicing machines, and primarily to a type employing a rotative cutter.

An object of the invention is directed to sharpener means for the rotative cutter readily movable into and out of commission and operated through the transmission devices for rotating the cutter.

Other features and advantages will be more fully set forth in the description of the 20 accompanying drawings, forming a part hereof, and disclosing a preferred embodiment of the invention, and in such drawings, like characters of reference denote corresponding parts throughout the several views, 25 of which:

Figure 1 is a top plan view of the complete slicing machine.

Fig. 2 is a longitudinal vertical section.

Fig. 3 is a front rear elevation.

30 Fig. 4 is a detail section on line 4-4, Fig. 1.

Fig. 5 is a detail elevation of the table.

In the machine illustrated in the drawings, the material to be sliced is manually 35 fed or slid over stationary table sections relatively disposed at different elevations to a degree proportionate to the thickness of slice to be delivered by the machine. A rotative knife intervenes the table sections to 40 intercept and cut the material bulk as it is fed or slid from one table section to and upon the second table section, the cutting edge of the knife being substantially flush with the upper surface of the second table 45 section during its rotative travel through the cutting zone. Upon being returned to the first table section, the material bulk descends by gravity to a successive slice cutting elevation, the first table section being 50 vertically adjustable to determine the slice thickness.

The first or front table section is provided with a surface plate 32 of glass or similar material adjustably and detachably

secured thereto by an improved form of retaining means, and an improved form of knife sharpening attachment is provided for grinding or sharpening the knife when necessary.

The frame of the machine consists of two 60 parallel side rails 1, having circular rear ends 2, which form a housing for the circular knife 3. These rails are integrally joined by cross-webs 4, 5, 6, and are provided with suitable supporting legs 7.

The circular knife 3 is a steel casting of dish-form in cross section, offsetting the margin knife tang from its central web to provide a table receiving recess, enabling the table surface to be alined flush with the plane 70 upper tank side 8. The knife is secured to a hub disk 9, which is supported upon a boss projecting from the cross-web 5, and secured to a vertical shaft 10 journaled in said web.

Manual means, as a hand wheel, is provided for revolving the knife, said hand wheel being secured to the outer end of a horizontal shaft 11 journaled in the cross web 5. The inner end of the shaft 11 has a beveled gear 12, fixed thereon in mesh with 80 a beveled pinion 13, fixed to the knife shaft 10, providing a direct drive between the hand wheel and knife.

A curved guide plate 14 is secured to the cross-web 4, at 15, and extends upwardly to 85 a point closely adjacent the cutting edge of the knife to guide or direct the slice downwardly and away from the drive gears.

The table section 16 is represented as a dish formation of a circular outline to provide offset marginal sides 17, defining longitudinal side walls 18 for confining the slicing area laterally. It has a portion thereof cut away, visible in Fig. 1, for clearance for the knife and for continuity of travel of the 90 material bulk from one table section to the second, and also, for the purpose of seating the forward table edge within the knife recess and approximately flush with the upper 95 surface of the knife tang. The table section 16 is secured by thumb screws 19, to lugs 20, which project upwardly from the frame, the forward edge being within the knife recess and the rear edge-extending beyond and above the knife.

The front table section is adjustable to different predetermined elevations to gage the thickness of the slice. The base plate

21 of said table section is secured upon a bracket plate 22, fixed to a vertical supporting rod 23, said rod being slidably supported within laterally extended spaced portions of the cross-web 6. To guide the base plate 21 in its vertical movements of adjustment and confine the table against rotation, I provide screws 24 screw threaded into the rails 1, and engaging the side walls 10 25 of the base plate. The rod 23 and its elements are adjusted vertically by a cam lever 26, having a tubular or sleeve portion 27 straddled by the cross-web 6, to confine the same against longitudinal movement 15 with the rod, although rotative thereon. The sleeve is provided with an angular slot 28, into which a radially projected pin 29, fixed into the rod, engages and slides, the angle of the walls of the slot determining the degree of adjustment of the table in an oscillating movement of the lever. The lever 26 has an indicator point 30 projected therefrom, which moves over an indicator dial 31, projecting from the web 6. Thus by 20 25 swinging the lever either to the right or left, the front table section can be elevated or lowered and can be delicately adjusted, coördinate to the cutting plane of the knife to determine the thickness of the slice and 30 maintain it in its adjusted position. The glass surface plate 32 is supported on the base plate 21 and is confined against lateral displacement by the side walls 25 thereof. A pair of retaining plates 33 engage the 35 longitudinal upper edges of the surface plate to prevent vertical movement thereof, said retaining plates extending beyond the front edge of the surface plate, at which point they are provided with inturned abutment lugs 34. The surface plate 32 has a 40 circular beveled rear edge which is engaged by an upturned lip 35 of a clamp slide 36, which is slidably mounted in a recess in the base plate 21 and provided with screw threaded translator means 36^a for translating the clamp slide to clamp the surface plate against the abutment lugs 34. The retaining plates 33 are adjustably clamped to the side walls 25 of the base plate 21 by 45 50 bolts 37 secured in said plates and projecting through elongated slots 38 in the side walls of the base plate. This permits a longitudinal adjustment of the surface plate relative to the knife.

55 Means are combined with the machine for grinding or sharpening the knife at any time meeting the pleasure of the operator, or if sharpening is required, without removing any of the parts and operated by the 60 hand wheel rotating the knife. The sharpening attachment is permanently located on the machine and is readily thrown into and out of commission. It is supported at the rear medial portion of the machine below 65 the knife and dependingly from the cross-

web 4 and horizontal drive shaft 11. A bracket arm 40 loosely journaled on the shaft 11 projects downwardly and rearwardly and has loosely journaled in its lower end a rock shaft 41, to which is secured an H-bracket arm 42. Rotatively journaled in the bracket arm 42 is a shaft 43, on one end of which is detachably secured a grinding wheel 44, the other end having fixed thereto a gear pinion 45, 70 75 adapted to be thrown into mesh with a gear wheel 46 secured to the inner face of the hand wheel 47. The bracket arm 42 has secured thereto a handle 48 which extends inwardly as at 49, and is provided with a laterally projecting pin 50, normally engaged into a retaining notch 51, formed in a guide plate 52 secured to and projecting downwardly from the cross-web 4. The notch 51 merges into a guide slot 53, which 80 is concentric with the shaft 11 and serves to hold the pinion 45 in mesh with gear 46 during the vertical travel of the grinding attachment. A coil spring 54 surrounds the rock shaft 41, one end being secured to the 90 shaft, and the other end secured to the bracket 42. This spring exerts its tension to hold the pin 50 in the retaining notch 51. The rock shaft 41 extends beyond the bearings of the bracket arm, see Fig. 3, and interposed between it and the frame 2 is a spring 55 which exerts its tension to elevate the grinding attachment to bring the grinding wheel 44 into engagement with the knife. An adjustment screw 56 is mounted 100 in the cross bar of the bracket arm 40, the upper end engaging the cross-web 4 when the grinding attachment is in commission, to determine the degree of grinding contact between the grinding wheel 44 and knife. 105

I claim:—

1. In a machine of the class described, a rotative grinding wheel, toggle lever means as a movable bearing support for the grinding wheel, yieldingly urged to move said wheel toward a cutter, and one yieldingly urged upon the other in a direction laterally to the motion toward the cutter, for maintaining said wheel in an inoperative position, a guide for directing the motion of said lever means, a main driving gear, and a gear fixed to the axis of said grinding wheel movable therewith, to engage with said first-named gear for rotating the grinding wheel. 110 115 120
2. In a machine of the class described, a rotative grinding wheel, toggle lever means as a movable bearing support for the grinding wheel, yieldingly urged to move said wheel toward a rotative cutter, and one yieldingly urged upon the other in a direction laterally to the motion toward the cutter, for maintaining said wheel in an inoperative position, a guide for directing the motion of said lever means, adjustable means 125 130

for determining the limit of motion of said lever means toward the cutter, a driving gear, and a gear fixed to the axis of said grinding wheel movable therewith, to engage with the said first-named gear and in mesh toward the cutter.

5 In witness whereof, I hereunto subscribe

my name, as attested by the two subscribing witnesses.

ALBERT KRAUTH.
